UNITED STATES PATENT OFFICE

JAMES MELVIN JONES, OF HAMILTON, ONTARIO, CANADA.

SAFETY-GUARD.

1,001,858.

Specification of Letters Patent. Patented Aug. 29, 1911.

Application filed March 9, 1911. Serial No. 613,370.

To all whom it may concern:

Be it known that I, JAMES MELVIN JONES, a citizen of the Dominion of Canada, residing at 22 King William street, in the city of 5 Hamilton, in the county of Wentworth, in the Province of Ontario, Dominion of Canada, have invented a certain new and useful Safety-Guard, of which the following is a specification.

10 This invention relates to a safety guard and it has more particular reference to that type of device which is adapted for use upon punching, stamping, cutting, embossing and drawing presses and similar machines as a 15 safeguard against the operator's fingers or hands getting caught when the operative parts are brought into use.

My invention has special reference to the gate and its appurtenant parts which are 20 moved up and down in front of the operative parts by means of a fulcrumed lever and it has for its objects to provide a gate for safety guards for stamping presses and the like which is adjustable laterally and 25 vertically to adapt itself to different widths and sizes of presses or machines, while at the same time it effectively guards the ends of the dies or cutters. I attain these objects by the mechanism illustrated in the accompanying sheet of drawings, in which:—

Figure 1, is an elevation of the complete guard as attached to the fulcrumed lever which raises and lowers the same. Fig. 2, is a 35 top plan of the same. Fig. 3, is an end view looking to the left of Fig. 1. Fig. 4, is a detail view of the sliding block which couples the safety guard to the fulcrumed lever. Fig. 5, is a central vertical section of the same taken at right angles to Fig. 4. Fig. 6, is an 40 isometric view of the block carrying the gate supporting arm or bar. Fig. 7, is a detail transverse section of the means for connecting together the laterally movable parts of the gate and the aforesaid supporting arm. Fig. 8, is a detail of a key-piece hereinafter 45 more specifically referred to.

Like reference numerals designate the same or similar parts in the several figures.

In order that my invention may be clearly 50 understood I will now describe the same in conjunction with the above specified drawings, which exemplify one embodiment thereof as applicable for use on a stamping press of any of the ordinary and well known 55 types.

1, is a fragment of the front end of the fulcrumed lever which is pivoted at one side of the press for operating the guard gate, its arrangement and actuating connections being not illustrated as they form no part of 60 the present invention, and they will be readily understood by those acquainted with the art to which the invention appertains. The lever 1, is of rectangular cross section, and according to my invention I longitudinally 65 serrate or otherwise suitably tooth the upper face thereof at 2, for a predetermined distance.

3, is a bar of rectangular cross-section which is correspondingly serrated or toothed 70 transversely at 4, for a suitable distance along its lower face, said serrations or teeth being adapted for engagement by the serrations or teeth 2, aforesaid. This bar 3, is arranged to extend across the front of the 75 press when in position, and it is rigidly coupled to the fulcrumed lever 1, by means of a box-shaped block 5, which is provided with two lateral slots 6, 7, arranged at right angles to and one above the other but medially intersecting, as will be clearly understood on an examination of Figs. 4 and 5. The lower slot 6, is adapted to receive the end of the fulcrumed lever 1, and the upper slot 7, to receive the serrated end of the bar 85 3, and in order to firmly lock said parts together, I fit into a threaded bore 8, at the lower end of the block 5, a cap-screw 9. Thus it will be seen that by slackening the 90 cap-screw 9, the block 5, and bar 3, may be adjusted longitudinally of the end of the fulcrumed lever 1; or the bar 3, and block 5, may be withdrawn from the end of the fulcrumed lever 1, and said bar 3, adjusted 95 transversely either to the right or left hand, and replaced, whereupon the cap-screw 9, is tightened up and displacement in either direction effectively prevented.

10, is a second box-shaped block which is 100 provided with a lateral slot 11, adapted to receive the outer end of the aforesaid bar 3, to which it is rigidly coupled by means of a cap-screw 12, taking into a correspondingly threaded bore 13, and by this means said block may be adjusted in position at any 105 point along the bar 3.

14, is a vertical slot formed at the rear of the block 10, in which is fitted a depending arm or bar 15, which carries at its lower end the gate hereinafter fully described. 110

- The depending arm or bar 15, is formed at one of its upper edges with a laterally toothed or serrated portion 16, with which coöperates a similarly toothed or serrated 5 key-piece, 17, furnished at its upper and lower ends with lugs or ears 18, 18, which fit snugly against the top and bottom faces of the block 10, and prevent its displacement. Obviously the slot 14, is made sufficiently 10 wide to allow the key-piece play enough for the vertical adjustment of the arm 15; and 19, is a cap-screw fitting into a correspondingly threaded bore 20, for insuring locking engagement of the parts 16, and 17. 15 The lower end of the vertically depending arm or bar 15, is bent knee fashion at 21, and firmly driven into a correspondingly shaped slot 22, provided for its reception in a block 23.
- 20 24, is a cap-screw threaded into a correspondingly screwed hole 25 drilled into the block 23 through the lower end of the arm 15, as clearly shown by the sectional detail Fig. 6. Formed transversely of the block 25 23, is a second slot 26, in which are fitted the free ends of two bars 27, 28, bent at right angles and arranged on their edges, as will be clearly understood from an examination of Figs. 1, and 3. These bars 27, 28, 30 each have appropriately secured to their upper edges screen members 29, 30, respectively, which are cut away at 31, to allow for overlapping when the said bars, 27, 28, 35 are moved apart or closed together as will be clearly seen by an inspection of Figs. 1 and 2, the latter figure showing the expanded position in dot-and-dash lines. The free end 32, of the bar 27, is appropriately rounded off as shown by Figs. 2 and 7, to 40 permit the screen members 29, 30, being, brought as close as possible together. The cap-screw 24, above referred to, serves also to lock the bars 27, 27, in adjusted relation, and it will be apparent that said bars may 45 be shaped to any other desired angle in plan to suit different types and widths of dies or cutters.
- From the foregoing description it will be seen that by my invention, I have effected a very great improvement in safety guards 50 of the type referred to, perfect adjustability in all directions being provided, and at the same time when the several parts are properly adjusted rigid locking thereof is positively insured. 55
- In practice I have found the improved safety guard extremely effective for the purposes specified, and I do not limit myself to the specific details of construction particularly described and shown, many alterations 60 and various other combinations thereof being possible without in any way departing from the field and scope of the invention, and it is intended to include all such within this application, wherein only the preferred 65 form has been exemplified.
- Having described my invention, what I claim as new and desire to secure by Letters Patent, is:—
- The combination with the fulcrumed lever 70 of a safety guard for machines of the types hereinbefore specified, of a bar one edge of which is adapted for interlocking coöperation with the aforesaid fulcrumed lever, means for coupling said parts in interlocking relation, a laterally adjustable block adapted for rigid fixture on the said bar and carrying a vertically adjustable arm, means for maintaining said arm rigid when adjusted, a second block securely fixed to the 75 lower end of said vertically adjustable arm, and laterally adjustable screen members carried by said block, substantially as set forth for the purpose specified. 80
- Signed at Hamilton, Ontario, this 2nd 85 day of March, 1911.
- JAMES MELVIN JONES.
- In the presence of—
- GERTIE NICHOLSON,
ALFRED Y. BRATTON.
